In the Netherlands May 2, 1947

4 Claims. (Cl. 178—6.7)

1

This invention relates to receiving devices for image transmission in which the image is produced on a film moving along the recording device. In this case the image may be produced on the film, for example, by photographic means, the film for this purpose being provided with a photosensitive layer and scanned by a light beam, modulated by image signals, for example in parallel paths at right angles to the direction of movement of the film. Subsequently the exposed film is developed.

It is, in this case, frequently desirable to have the film, prior to development, cut into pieces of approximately equal length and this must, of course, be effected in such manner that the film is cut precisely between two images, independently of the position of the images on the film.

This may be achieved by providing on or in the film, for example, marks in form of punched holes or notches in those parts of the film which are located between two successive images; at these marks the film is afterwards cut off. Also for other purposes it may be desirable to provide marks at each recorded image, for example, if it is desired to have the movement of the film automatically stopped when images are no longer recorded, or if it is desired to copy with a completely automatic device. The marking device to be used may be adapted to operate automatically and to be controlled by a signal emitted at the transmitter side during the interval between the transmission of two successive images. However, difficulties are then involved, since the said part of the film is located in the scanning space at the beginning of the recording operation, i. e. when the mark is required to be provided, and it is in general not possible, for mechanical reasons, to arrange in addition a marking device in the said space. Since it is furthermore of paramount importance that the film should pass along the scanning device at constant speed, it is not advisable to provide the marks at this area. Consequently, the mark is required to be provided outside the device for recording the image. In order to ensure, nevertheless, that a mark is provided at the beginning of each image, the marking device comprises, according to the invention, a first marking member which provides, under the action of the said signal, a mark in the film at an area which has already passed by the area at which the image is or will instantaneously be recorded, near the path of the film provision being made of a contact device which is operated when, during the movement of the film, the marked area passes the contact device. The

2

latter actuates a second marking member which provides a mark at that area of the film at which the recording of an image has started or ended. The first mark may be indicated as a preliminary mark and the second as a definite mark. The definite mark must be applied in such manner as to be not located in the path of the preliminary mark.

10 The definite mark may, for example, serve to control a cutting device for the film band. For this purpose such a device may be actuated under the action of a second contact device provided near the path of the film and which responds when, during the further movement of the film, the area of the film marked by the second marking member passes the second contact device. The device may be readily constructed in such manner that the film is invariably cut between two successive images.

15 20 According to the invention, if it is desired to cut pieces of definite length having a plurality of images instead of each image separately, provision is made for this purpose of means which will be further described hereinafter.

25 30 The invention will now be explained more fully with reference to the accompanying drawing, in which Fig. 1 shows the mechanical part of the apparatus according to the invention (all parts which are not essential to the invention being omitted). Fig. 2 shows the electrical circuit-diagram.

35 Referring to Fig. 1, reference numeral 21 designates a film on which the transmitted images are recorded in succession by photographic means. This film is subsequently cut into definite parts of approximately equal length, which are conveyed to a developing device for photographic pictures (not shown). Since the dimensions of the recorded images in the direction of length of the 40 film are not always the same and since, furthermore, the distances between successive images may vary, the portions cannot be of exactly the same length if it is desired to have the film invariably cut between two successive images. 45 Consequently, according to the invention, provision is made of particular means which ensure that the cutting operation is invariably carried out between two successive images.

50 The unexposed film is drawn, with the use of means which will be described more fully hereinafter, from a drum 22, passes over a roller 23, passes by a scanning device 29 and moves on between pairs of rollers 24 and 25. Arranged between these pairs of rollers are the two marking devices P₁ and P₂ which, on becoming operative,

provide the film with a mark, for example, a hole or a notch. Furthermore a contact device α_2 arranged alongside the path of the film becomes operative when the marked part of the film passes by, for example, by means of a resiliently arranged member slipping at that instant through the hole or the notch, thus closing a contact. A similar contact member α_1 is arranged beyond the pair of rollers 25. At this area is furthermore arranged the cutting device Sch, which may comprise a pair of scissors 23. The film is exposed at A. A device 29 serves to move the modulated light beam in parallel paths at right angles to the film and for this purpose it is rotatable about a shaft parallel to the longitudinal direction of the film. Driving is ensured by an electric motor M.

The device shown in Fig. 1, roughly speaking, operates as follows:

When the signal emitted between two images ceases and, consequently, the recording of the image starts, the relay RL₆ becomes de-energized, so that the device P₁ becomes operative with the result that, for example, a hole is punched in the film. When during the further movement of the film this hole reaches the area of the contact member α_2 , a circuit is closed which comprises the winding of the punching member P₂, so that a second hole or notch is formed in the film, preferably, however, in a manner different from the first, so that the two marks may be distinguished from one another. If provisions are made that the distance between the exposure area A and the punching member P₁ is equal to the distance between the contact member α_2 and the punching member P₂, the second mark is provided exactly at the beginning of each recorded image. This is invariably the case, even if the movement of the film is not quite uniform. The said second mark may thus serve to control a second contact member α_1 , which is included in a control circuit of the cutting device Sch.

If no further steps were taken, each image would be cut off separately, since the signal which on ceasing actuates the punching member P₁ is repeated after each image. However, it is, as a rule, desirable to cut off a definite length of say 50 cms. of the film, comprising a plurality of images. Furthermore the film transport must be stopped if exactly before the cutting operation a film portion of about 50 cms. of length comprising no images has passed the point A, so that there are no further exposed images in the receiver, whereas the film transport must be resumed as soon as an image appears.

These purposes are served by the contact devices driven by a shaft 31 shown in Fig. 1. The electrical diagram of these devices is shown in Fig. 2, which furthermore shows the energizing circuits for the punching and cutting members already described.

Through a worm gear 41 and a coupling 30, the shaft 31 of Fig. 1 is driven by the same electric motor M, which also serves to drive the scanning device. The coupling 30 is an electrical coupling which becomes inoperative as soon as the winding K₁ becomes conductive. The film 21 is also moved onwards from the shaft 31. This is carried out by driving wheels 32 and 33, the latter of which is coupled to one of the wheels 24, for example, by means of gear-wheel transmission. The said shaft 31 furthermore carries a driving wheel 36, which is coupled to one of the driving rollers 25. The movement by the rollers 25 is slightly more rapid than that by the rollers 24,

to such an extent that the rollers 25 exhibit a slight slip, the film thus being constantly kept taut between the said pairs of rollers. The shaft 31 has furthermore seated on it a cam disc 35, the cam of which successively actuates the contact members b_1 , b_2 and b_3 when the disc turns. The shaft 31 is furthermore coupled, through an electrical coupling 31, to a shaft 39, the latter being only driven by the shaft 31 when the winding K₂ of the coupling 31 is energized. The shaft 39 can only be turned through a definite angle and returns, on being released, under the action of a spring 40 until it engages an abutment. It furthermore carries a cam disc 38, the cam of which actuates in succession contact members d and e when the shaft turns.

Connected between the conductors 1 and 2 of Fig. 2 is a voltage source which supplies the energising current for the punching and cutting members, for a number of relays RL₁ to RL₅ and RL₇, for the windings K₁ and K₂ and for two pilot lamps L₁ and L₂. The voltage of this source is, for example, 12 volts. The contacts of the relays are designated by the same reference numerals 20 as the windings thereof. The numerals 1 to 23 of Figs. 1 and 2 have reference to identical points of contact in the circuit. Fig. 2 also shows the contacts which are controlled in Fig. 1, by the cam discs and the holes punched in the film.

The operation of this part of the device is as follows:

If, at the transmitter end, an image is not scanned, so that no image signals proper are emitted, a special signal is emitted, which, upon reception, produces at the receiver end, between the terminals 17 and 18 of Fig. 2, a current which causes the relay RL₆ to respond. When the scanning of an image at the transmitter end starts, this signal ceases and the relay RL₆ is de-energised, so that the contact of RL₆ reaches the position shown in Fig. 2 and the punching device P₁ is operated. The arrangement may readily be constructed in such manner that the punching member, after having punched a hole or a notch in the film, returns to its initial position, so that the movement of the film is not hindered by the punching member.

After the film has moved over a given distance, the hole punched by P₁ passes by the contact member α_2 , which is then closed, so that the punching member P₂ becomes operative and, furthermore, the relay RL₅ responds. Consequently, a second hole or notch is punched in the film, preferably in the opposite margin, so that the contact member α_2 does not respond when this second hole passes by the member α_2 .

The cam disc 35 serves to ensure that invariably definite portions of the film of about 50 cms. of length are cut off since, when a length of film of about 50 cms. has been wound off, the cam of the disc 35 has turned to such an extent that the contact b_1 is closed. Thus the relay RL₁ is energized and retains its energy through the contact RL₁. Consequently, RL₁ continues to be conductive till the relay RL₃ responds and opens the circuit of RL₁. The response of RL₁, moreover, initiates the closure of the circuits of K₂, RL₇ and of Sch and RL₃. When the next punching hole has arrived at α_1 , the contact α_1 is closed and K₂ becomes energized. The circuit of K₂ remains closed even when the punching hole has passed α_1 , since at the same time the relay RL₇ responds, which maintains itself energized through its contact RL₇. The disc 38 sets rotating and closes, 70 at a given instant, the contact d , thus closing the

circuit of the cutting member *Sch*, which had been initiated by the response of *RL*₁, with the result that the film is cut off. The position of the contact *d* is chosen to be such that contact takes place exactly at the instant when the punched hole, which brought about the closure of *a*₁, has arrived under the pair of scissors. Consequently, cutting off cannot take place before the contact *b*₁ is closed and about 50 cms. of film has passed by the pair of scissors. The relay *RL*₃ 10 is connected in parallel with the winding of *Sch*, so that, in addition, this relay responds and the relay *RL*₁ is again de-energized. Consequently, the coupling 37 becomes interrupted and the disc 38 returns to its initial position. The winding *K*₁ invariably remains non-energized, so that the disc 35 continues rotating, thus at first contact member *b*₂ and then *b*₃ becoming operative. The former has no effect, since *RL*₁ has become de-energized. The effect of the closure of *b*₃ will be evident from the following. When the disc 35 has reached its initial position, the original state is restored and the operation described may start again.

If, after about 50 cms. of film has passed, the contact *b*₁ is closed and the relay *RL*₁ responds, with the film having no marks, however, the contact *a*₁ will not be closed. The next operation depends upon the position of the relay *RL*₂. If since the cutting of the film neither of the punches *P*₁, *P*₂ has been operative, this shows that there are no images on the film which is still in the receiver. The contact of *RL*₆ in the circuit of *RL*₂ is thus open and the relay *RL*₂ is not energised. If, after *b*₁ has been closed, the maximum length of image plus the distance between *a*₁ and *Sch* has passed by, the contact member *b*₂ is actuated. The relay *RL*₄, which was energized through *b*₂, *RL*₁ and *e*, thus becomes interrupted, so that the contact *RL*₄ arrives at the position shown and the winding *K*₁ becomes energized. The coupling 39 is then interrupted and the film transport stops. In addition, the scissors *Sch* cut the film and the relay *RL*₁ becomes de-energised.

If, on the contrary, the relay *RL*₂ is energised, which means that there are, indeed, images in the receiver, *RL*₄ will not be de-energised when *b*₂ is closed. The film is in this case cut off, it is true, but the film transport continues. If, subsequently, *b*₃ is temporarily opened, so that *RL*₂ is de-energised, *RL*₄ remains energised through the contacts *RL*₄ and *RL*₁ and the transport is not interrupted.

The contact *b*₃ interrupts the circuit of *RL*₂ once during each revolution of the shaft 31, thus de-energising *RL*₂. Then *RL*₂ becomes again energized by the next punching operation through the contacts of *RL*₅ and *RL*₆ and maintains itself in the energised position. The contact *e* is a safety contact which stops the transport if the arrangement described should be disturbed.

After the film transport has been stopped by the contact *b*₂ in the manner above described, it is resumed when the special signal ceases, which is emitted when no image signals proper are emitted. The relay *RL*₆ is then de-energised again, so that the punching device *P*₁ becomes operative. Subsequently, the relay *RL*₂ is reenergised and then the relay *RL*₄, which remains energized through its contact *RL*₄. Consequently, the film transport is resumed.

The relay *RL*₂ is de-energised immediately after the start of the film transport, since *b*₃ is actuated immediately after *b*₂.

What we claim is:

1. A receiving device for image transmission, in which the images are produced with space portions therebetween on a reproduction film moving in a predetermined path, and said path in one part thereof being along an image recording device, comprising; a film marking device for producing a pair of marks on said reproduction film, transmission means including a device for scanning the original film to be reproduced, means for controlling operation of said reproduction film marking device, said last-named means being responsive to a signal which is produced by said transmission scanner device when said space portions of said original film between two successive images is scanned, said marking device comprising; a first marking member constructed and arranged to produce a mark in said reproduction film at an area remote from a limiting edge of said image, a contact device arranged near said path of said reproduction film for sensing when said mark passes by said contact device, a second marking member, and means responsive to said sensing action by said contact device for actuating said second marking member to produce a second mark in that area of said reproduction film at which the recording of the image is limited.
2. A receiving device for image transmission, 30 in which the images are produced with space portions therebetween on a reproduction film moving in a predetermined path, and said path in one part thereof being along an image recording device, comprising; a film marking device for producing a pair of marks on said reproduction film, transmission means including a device for scanning the original film to be reproduced, means for controlling operation of said reproduction film marking device, said last-named means being responsive to a signal which is produced by said transmission scanner device when portions of said original film between two successive images is scanned, said marking device comprising; a first marking member constructed 35 and arranged to produce a mark in said reproduction film at an area remote from a limiting edge of said image, a contact device arranged near said path of said reproduction film for sensing when said mark passes by said contact device, a second marking member, and means responsive to said sensing action by said contact device for actuating said second marking member to produce a second mark in that area of said reproduction film at which the recording of the image is limited.
3. A receiving device for image transmission, 40 in which the images are produced with space portions therebetween on a reproduction film moving in a predetermined path, and said path in one part thereof being along an image recording device, comprising; a film marking device for producing a pair of marks on said reproduction film, transmission means including a device for scanning the original film to be reproduced, means for controlling operation of said reproduction film marking device, said last-named means being responsive to a signal which is produced by said transmission scanner device when portions of said original film between two successive images is scanned, said marking device comprising; a first marking member constructed 45 and arranged to produce a mark in said reproduction film at an area remote from a limiting edge of said image, a contact device arranged near said path of said reproduction film for sensing when said mark passes by said contact device, a second marking member, and means responsive to said sensing action by said contact device for actuating said second marking member to produce a second mark in that area of said reproduction film at which the recording of the image is limited; cutting means for said reproduction film, and means for actuating said cutting means, said actuating means being responsive to said second mark.
4. A receiving device for image transmission, 50 in which the images are produced with space portions therebetween on a reproduction film moving in a predetermined path, and said path in one part thereof being along an image recording device, comprising; a film marking device for producing a pair of marks on said reproduction film, transmission means including a device for scanning the original film to be reproduced, means for controlling operation of said reproduction film marking device, said last-named means being responsive to a signal which is produced by said transmission scanner device when portions of said original film between two successive images is scanned, said marking device comprising; a first marking member constructed and arranged to produce a mark in said reproduction 55 film at an area remote from a limiting edge of said image, a contact device arranged near said path of said reproduction film for sensing when said mark passes by said contact device, a second marking member, and means responsive to said sensing action by said contact device for actuating said second marking member to produce a second mark in that area of said reproduction film at which the recording of the image is limited.
5. A receiving device for image transmission, 60 in which the images are produced with space portions therebetween on a reproduction film moving in a predetermined path, and said path in one part thereof being along an image recording device, comprising; a film marking device for producing a pair of marks on said reproduction film, transmission means including a device for scanning the original film to be reproduced, means for controlling operation of said reproduction film marking device, said last-named means being responsive to a signal which is produced by said transmission scanner device when portions of said original film between two successive images is scanned, said marking device comprising; a first marking member constructed and arranged to produce a mark in said reproduction 65 film at an area remote from a limiting edge of said image, a contact device arranged near said path of said reproduction film for sensing when said mark passes by said contact device, a second marking member, and means responsive to said sensing action by said contact device for actuating said second marking member to produce a second mark in that area of said reproduction film at which the recording of the image is limited.
6. A receiving device for image transmission, 70 in which the images are produced with space portions therebetween on a reproduction film moving in a predetermined path, and said path in one part thereof being along an image recording device, comprising; a film marking device for producing a pair of marks on said reproduction film, transmission means including a device for scanning the original film to be reproduced, means for controlling operation of said reproduction film marking device, said last-named means being responsive to a signal which is produced by said transmission scanner device when portions of said original film between two successive images is scanned, said marking device comprising; a first marking member constructed and arranged to produce a mark in said reproduction 75 film at an area remote from a limiting edge of said image, a contact device arranged near said path of said reproduction film for sensing when said mark passes by said contact device, a second marking member, and means responsive to said sensing action by said contact device for actuating said second marking member to produce a second mark in that area of said reproduction film at which the recording of the image is limited.

film at an area remote from a limiting edge of said image, a contact device arranged near said path of said reproduction film for sensing when said mark passes by said contact device, a second marking member, and means responsive to said sensing action by said contact device for actuating said second marking member to produce a second mark in that area of said reproduction film at which the recording of the image is limited; cutting means for said reproduction film, means for actuating said cutting means, said actuating means including a contact device engageable with and responsive to said second mark.

4. A receiving device for image transmission, in which the images are produced with space portions therebetween on a reproduction film moving in a predetermined path, and said path in one part thereof being along an image recording device, comprising: means for moving said reproduction film in said predetermined path, a film marking device for producing a pair of marks on said reproduction film, a transmission means including a device for scanning the original film to be reproduced, means for controlling operation of said reproduction film marking device, said last-named means being responsive to a signal which is produced by said transmission scanner device when space portions of said original film between two successive images is

10 15 20 25 30

scanned, said marking device comprising; a first marking member constructed and arranged to produce a mark in said reproduction film at an area remote from a limiting edge of said image, 5 a contact device arranged near said path of said reproduction film for sensing when said mark passes by said contact device, a second marking member, and means responsive to said sensing action by said contact device for actuating said second marking member to produce a second mark in that area of said reproduction film at which the recording of the image is limited; and means for rendering said reproduction film moving means inoperative when no recorded images are sensed by said scanning device.
